UNITED STATES PATENT OFFICE.

ADON J. HOFFMAN, OF SEATTLE, WASHINGTON.

CLOTHES-PRESSING APPARATUS.

No. 928,199.

Specification of Letters Patent.

Patented July 13, 1909.

Application filed December 1, 1904. Serial No. 235,118.

To all whom it may concern:

Be it known that I, ADON J. HOFFMAN, a citizen of the United States of America, and a resident of the city of Seattle, in the 5 county of King and State of Washington, have invented certain new and useful Improvements in Clothes-Pressing Apparatus, of which the following is a specification.

My invention pertains to certain new and 10 useful improvements in clothes pressing apparatus, and has for its object a device of this type which in its operation will simultaneously dampen or moisten and press the clothes.

15 The invention consists in the novel construction, arrangement and combination of parts to be fully hereinafter referred to and pointed out in the appended claims.

In the accompanying drawings:—Figure 20 1, is an end elevation of my improved device, the press head being in partial section taken on line 1, of Fig. 4, Fig. 2, is a fragmentary longitudinal section on line 2, of Fig. 4, Fig. 3, is a top plan view of the 25 press block, showing its supports in dotted lines, and Fig. 4, is a top plan view of my improved device, portions being broken away and parts removed. Fig. 5 is a section through a pressing block used in connection with the present invention. Fig. 6 30 is a section through an air intake valve forming part of the present invention.

In the embodiment of my invention a base 35 designated at 1, is employed which supports a press block 2, and a press head 3, movable one in relation to the other, as shown in the present case the press block being rigidly supported and the press head movably mounted with respect thereto.

40 For the purpose of the present invention the press block may be of the usual and well known form, shown in Fig. 3, a facing of cloth 4, being employed which overlies padding 4' shaped to impart a convex contour 45 to the press block face.

The press head is hollow and preferably 50 of the form shown, conforming in outline to the press block, and comprises a base 5, formed with a depending marginal flange 6, and elongated dome 7, which is disposed centrally of the base and spaced from the periphery of the same. The base 5, forms in conjunction with the sides of the dome and a covering 8, a heating chamber 9, entirely surrounding the dome. Covering 8, 55 for the purposes of the present invention is

formed with a short depending marginal flange 10, which abuts the sides of dome 7, and a like flange 11, of greater width than flange 10, for the purpose of engagement 60 with and securement to flange 6, the securement being preferably effected by means of screws 12.

In the present disclosure I have shown a pair of burners, 13, 14, of U-form disposed 65 so as to conjointly embrace the dome. The burners are identical duplicates of each other, a detail description of one therefore sufficing for the other. Burner 13, comprises a tubular member 15, whose ends are 70 curved inwardly as at 16, forming elbow connections with pieces of pipe 17, whose inner ends are suitably closed with stops 18. Member 15, is formed with a central tubular part 18, to which is threaded an air and gas 75 mixer 19, provided with valve 20, to govern the intake of air, and tube 21, for the admission of gas, said tube leading to the source of supply. The burners are spaced from base 5, which is accomplished by seating the 80 burners on ribs 22, formed on base 5, clips 23, being employed which are secured to the base at their lower ends and curved at their opposite ends to embrace the tubular member 15, for the purpose of rigidly retaining 85 the burners in position.

The burners are formed with a series of 90 gas outlets 24, disposed radially and arranged so as to direct the flame at points coincident with the junction of base 5, and the sides of the dome, for a purpose to be hereinafter set forth.

The press head further embodies a deflector 25, here shown in the form of a plate disposed at a distance below the top of dome 95 7. The mode of supporting deflector 25, may be, as shown, by means of spacing sleeves 26, through which pass bolts 27, the heads of which engage the under sides of deflector 25, and the opposite ends of which are threaded 100 into engagement with bosses provided on the under side of dome 7. By reference to Fig. 2, of the drawings it will be observed that deflector 25, extends in proximity to the point of juncture of the sides of dome 7, and the base 5, being but slightly spaced from said point of juncture.

To the marginal flange 6, a concave plate 28, is secured preferably by means of screws 29, this plate being formed throughout its 110 area with perforations 29, and being spaced from deflector 25. It will be observed that

concave plate 28, has its degree of curvature corresponding to the degree of curvature of the convex face of press block 2, enabling the press head and press block to act in conjunction when operating on clothes. Plate 28, is faced with a section of cloth 30, which is turned upwardly to engage the outer sides of the flange 11, of covering 8, preferably being retained in engagement by means of a securing wire 31, which is drawn taut to firmly secure the cloth.

Dome 7, is formed with a steam inlet 31, disposed centrally thereof, and to which a pipe 32, is connected, a controlling valve 33, being interposed in said pipe to govern the ingress of steam. Pipe 32, is connected to a pipe 34, the latter being connected to a pipe 34'; a swivel joint 35, being employed between pipe 34', and a pipe 36, which leads to the steam source of supply, this swivel manifestly being for the purpose of accommodating movement of the press head.

It will be observed that deflector 25, serves to divide the hollow press head into an upper and a lower chamber, in communication with each other by virtue of a passage formed by the deflector terminating at a point adjacent to the dome sides, this passage as previously stated being at a point coincident with the point at which the burner flames are directed. Steam upon entering the upper chamber through inlet 31, is encountered by deflector 25, the steam upon expanding seeking the said passage and passing downwardly into the lower chamber where it again expands and completely fills the lower chamber. The steam in egressing through the apertures of plate 28, has its moisture absorbed by the cloth facing of said plate, and by reason of said cloth facing being in contact with the clothes being pressed imparts the necessary moisture to the latter, as well as heating plate 28, to a degree of temperature sufficient for the purpose of pressing. It will therefore be obvious that during the entire operation a certain proportion of moisture will be imparted to the clothes, it being possible, however, to cut off the ingress of steam, after the press head has become heated to a degree sufficient for the purpose, by operation of controlling valve 33.

A valuable adjunct to my invention is in the nature of the burners, whose function it is to superheat the steam during the time of its passage from the upper into the lower chamber, at which period the steam is egressing into the lower chamber through a passage of comparatively small area, thereby completely subjecting the steam to heat from a flame of great intensity.

The press head is swingingly mounted for movement to and from block 2, the head being supported by arms 37, 37, secured thereto and to a shaft 38, the latter having

its bearings in standards 39, 39, suitably secured to the base 1. Preferably the axis of rotation of the press head is in the same horizontal plane as the face of the press block 2, for the purpose of allowing the operating faces of the press block and press head to contact throughout enabling a uniform pressure on the clothes.

In the present disclosure I have shown the means for imparting movement to the press head as comprising arm 40, splined to shaft 38, and connected to a rod 41, the lower end of the latter being pivoted to a foot lever 42, fulcrumed to hanger 43, which depends from base 1; a retractile spring 44, being connected to the base and the foot lever for returning the press head to normal position.

The present invention is designed for use in tailoring establishments as distinguished from laundries, in the former it being necessary that the clothes such as trousers, coats, skirts, and the like, be moistened previous to application of the heated pressing medium applied under considerable pressure. By the use of my invention separate operations for obtaining a dampening or moistening of the cloth and the pressing thereof are obviated, both being performed in one and the same operation.

Having thus fully described my invention, what I claim as new and desire to secure by Letters Patent is:—

1. In a garment pressing machine, a supporting bed for the garment, a foraminous presser plate permanently associated with and movable toward and from the upper surface of the bed, and means for projecting steam through the foraminous presser plate while the latter is in its pressing position.

2. In a garment pressing machine, a supporting bed for the garment, a presser head permanently associated with and movable toward and from the upper surface of the bed and provided with a steam chamber having a foraminous bottom, and means for introducing steam into said chamber and through the bottom thereof while the head is in its pressing position.

3. In a garment pressing machine, a supporting bed for the garment, a presser head permanently associated with and movable toward and from the upper face of the bed and provided with a steam chamber having a perforated bottom, a foraminous press cloth extending across the under side of the perforated bottom, means for moving the head toward and from the bed, and additional means for introducing steam into the chamber and through the perforated bottom and press cloth while the presser head is in its pressing position.

4. In a garment pressing machine, a supporting bed for the garment, a superposed

- presser head permanently associated with and movable toward and from the upper face of the bed and fixed from endwise movement relatively thereto, said presser head having a steam chamber and a perforated metal plate extending across the bottom of the steam chamber, a foraminous press cloth covering the bottom of the perforated plate, means for moving the head toward and from the bed, and means for introducing steam into the steam chamber and through the perforated plate and press cloth while the head is in its pressing position.
5. In a garment pressing machine, a supporting bed for the garment, a superposed presser head movable toward and from the bed and having a laminated foraminous bottom, and a steam chamber immediately above said bottom.
10. In a garment pressing machine, a supporting bed for the garment, a superposed presser head permanently associated with and movable toward and from the bed and provided with a steam chamber having a laminated foraminous bottom.
15. In a garment pressing machine, a supporting bed for the garment, and a superposed presser head movable toward and from the bed and provided with a steam chamber having a bottom composed of juxtaposed foraminous members, the foramina of the bottom member being finer than those of the top member.
20. In combination with an elongated press block, a hollow elongated press head, an elongated dome on said head spaced from the edges thereof, a perforated face plate carried by said head, a deflector in the head dividing the same into a pair of chambers, said deflector being spaced from the side walls of the dome to form a passage connecting said chambers, burners carried by the head and embracing said dome, said burners being disposed so as to direct the flame against said head, and means for supplying steam to the head.
25. In combination with a press block, a hollow press head, a dome on the head spaced from the edges thereof, a marginal flange depending from the base of the head, a perforated plate secured to said flange, a deflector in said head, burners carried by the head base and embracing said dome, a covering inclosing said burners, said covering abutting the dome and being secured to said flange, and means for supplying steam to said head.
30. In combination with a press block, a hollow press head, a dome on the head spaced from the edges thereof, a deflector in the head spaced from the side walls of the dome, burners carried by the head and embracing the dome, said burners being disposed so as to direct the flames against said
- head, and means for supplying steam to the head.
35. In combination with a press block, a hollow press head comprising a base, a perforated face plate carried thereby and a dome spaced from the edges of the base, a deflector in the head disposed in substantially the same plane as said base, burners embracing the dome, and means for supplying steam to the head.
40. A clothes pressing apparatus comprising a pressing head having an upper and lower portion, means for supplying steam to the upper part of said head, a deflector positioned within the head for directing said steam in a thin sheet to the lower part of the head, and means for heating said head at the point of contact of said sheet of steam with said head for superheating said steam.
45. A clothes pressing apparatus comprising a pressing head formed with a hollow upper portion and an enlarged hollow lower portion, a deflector positioned adjacent to the juncture of the upper and lower portions, means for applying steam to the upper portion, and means for heating the steam as it escapes from the upper portion to the lower portion.
50. A clothes pressing apparatus comprising a pressing head formed with an upper and lower portion, means for supplying steam to the upper portion of said head, a deflector positioned near the juncture of the upper and lower portions for directing the steam from the upper portion to the lower portion in a thin sheet, and means for forcing a flame against the said head at the juncture of the upper and lower portions for superheating the steam in its passage from the upper to the lower portion of said head.
55. A clothes pressing apparatus comprising a pressing head formed with a dome and an enlarged base formed integral with said dome, a deflector in said head dividing the same into an upper and a lower chamber, means for admitting steam into the dome, and burners embracing the upper chamber of the dome for heating the steam as the same passes into said lower chamber.
60. In a clothes press, a supporting bed for the garment, and means for applying direct mechanical and steam pressure to the upper surface of the garment, comprising a presser head having direct movement to and from the bed and provided with a steam chamber having a foraminous bottom forming a presser face of the head.
65. Signed at Seattle, Washington this 14 day of November 1904.
